UNITED STATES PATENT OFFICE

ARTHUR DICKMAN, OF CINCINNATI, OHIO, ASSIGNOR TO THE P. GOLDSMITH SONS COMPANY, OF CINCINNATI, OHIO, A CORPORATION OF OHIO

DESIGN FOR A FOOTBALL HELMET

Application filed November 29, 1929. Serial No. 33,582. Term of patent 7 years.

To all whom it may concern:

Be it known that I, ARTHUR DICKMAN, a citizen of the United States, residing at Cincinnati, in the county of Hamilton and State of Ohio, have invented a new, original, and ornamental Design for a Football Helmet, of which the following is a specification, reference being had to the accompanying drawing, forming part thereof.

In the drawing:

The figure is a perspective view of a football helmet showing my new design.

I claim:

The ornamental design for a football helmet substantially as shown.

ARTHUR DICKMAN.
